Gilbert L. Bailey

UNITED STATES PATENT OFFICE.

GILBERT L. BAILEY, OF PORTLAND, MAINE.

NET-STAFF.

SPECIFICATION forming part of Letters Patent No. 315,107, dated April 7, 1885.

Application filed August 25, 1884. (No model.)

To all whom it may concern:

Be it known that I, GILBERT L. BAILEY, a citizen of the United States, residing at Portland, in the county of Cumberland and State of Maine, have invented a new and useful Improvement in Net-Staffs, of which the following is a specification.

My invention relates to improvements in the head of that class of net-staffs used by fishermen for landing or dip nets in which an elastic or spring hoop is employed, and has for its objects to provide a net-staff head of such construction as to conveniently receive and firmly support the ends of an elastic hoop and permit the same to be easily removed, and having no separable parts to get lost or loose. I attain these objects by the mechanism illustrated in the accompanying drawings, in which—

20 Figure 1 is a vertical section of the head and a portion of the staff; Fig. 2, a top view of the head; Fig. 3, a detailed view in perspective of the head and a portion of the staff and hoop, and Fig. 4 a view of the hoop or strip of which the hoop is made.

25 Similar letters refer to similar parts throughout the several views.

My invention consists in a hollow cylinder or ferrule, D, terminating in a rectangular head, K, having a flat-bottomed recess, A, formed in its upper surface, with pins or studs G G rising therefrom, and slots F F opening into said recess from the under side of the projecting portions B B. Ferrule D is fixed 30 on the smaller end of staff E, which carries at its larger end a screw-butt cap or screw-capped ferrule, or, if preferred, an ordinary ferrule.

35 The net-hoop C is made of a narrow flat strip of spring-tempered metal, preferably brass, of a length to give the desired size of hoop, and has a small hole through it near each end, corresponding in size with studs G G.

To put the hoop in position for use, one end

is passed through slot F and over one of the 45 studs in recess A, then bent into the form of a hoop or ring, and the other end inserted in like manner at the opposite side of the head and over the stud on that side, as in the first case. The elasticity of the hoop causes the 50 end to be pressed firmly against the bottom of recess A and the adjacent portions against those of inverted slots F. The width of the hoop corresponds with that of the recess and slots, which, together with studs G G, prevents any lateral play or drawing out of the 55 hoop.

To remove the hoop, grasp it near one side of the head and bend it down until its end comes off the stud, then remove it from the 60 slot and let it straighten out, when the other end can be readily removed, and the strip placed within the staff, which may be made hollow for that purpose.

I am aware of the invention of Chas. F. 65 Nason, patent dated August 31, 1875, No. 167,189; also of O. M. Muncaster, dated Feb. 13, 1883, No. 272,305, and that of R. J. Welles, dated March 6, 1883, No. 273,651, and do not claim any part of their inventions; but, 70

Having described my invention, what I claim, and desire to secure by Letters Patent, is—

1. Head K, having recess A, slots F F, and studs G G, in combination with staff E and 75 elastic hoop C, substantially as herein described.

2. A net-staff head composed of one piece provided with a hollow cylindrical base, a recess in its upper surface, and slots or grooves 80 in portions of its under surface opening into said recess, adapted to receive and support the ends of an elastic net-hoop, substantially as herein set forth.

GILBERT L. BAILEY.
